Patented May 21, 1968

211,083

WHEEL COVER

Charles L. Burson, Ypsilanti, Mich., assignor to Gar Wood Industries, Inc., Wayne, Mich., a corporation of Michigan

Filed June 5, 1967, Ser. No. 7,356

Term of patent 14 years

(Cl. D14—30)

FIG. 1. is a front elevational view of a wheel cover showing my new design;

FIG. 2 is side sectional view taken substantially along the line 2—2 of FIG. 1;

FIG. 3 is a sectional view taken substantially along the line 3—3 of FIG. 1;

FIG. 4 is a perspective view.

I claim:

The ornamental design for a wheel cover, as shown.
